UNITED STATES PATENT OFFICE

124,823

DESIGN FOR A GAME BOARD

Boyd C. Rodkey, Cleveland, Ohio

Application November 4, 1940, Serial No. 96,294

Term of patent 7 years

To all whom it may concern:

Be it known that I, Boyd C. Rodkey, a citizen of the United States, residing at Cleveland, in the county of Cuyahoga and State of Ohio, have invented a new, original, and ornamental Design for a Game Board, of which the following is a specification, reference being had to the accompanying drawing, forming part thereof.

I claim:

The ornamental design for a game board, as shown.

BOYD C. RODKEY.
